(57) **CLAIM**

We claim the ornamental design for a housing for a device with dual solenoid valves, as shown and described.

DESCRIPTION

FIG. 1 is a perspective view of a housing for a device with dual solenoid valves;

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is a top view of the housing for a device with dual solenoid valves, with the unclaimed structure shown in broken lines of FIG. 6 in a different orientation to illustrate portions of the claimed design obscured in FIG. 6, the portions of the claimed design obscured in FIG. 8 and shown in the other figures remaining part of the claimed ornamental design.

The broken lines of FIGS. 1-8 depict environmental subject matter only and form no part of the claimed design.
